JAMES J. McCANN, OF KEARNY, NEW JERSEY, AND CHARLES G. BIRDSALL, OF ELM-
HURST, NEW YORK, ASSIGNEES, BY MESNE ASSIGNMENTS, TO NATIONAL CARBON
COMPANY, INC., OF NEW YORK, N. Y., A CORPORATION OF NEW YORK.

DRY CELL.

Application filed August 26, 1924. Serial No. 734,242.

This invention relates to new and useful improvements in liners for dry cells.

It is the object of the present invention to produce a liner adapted to separate the depolarizing mix from the zinc electrode, and one which may be produced by automatic machinery ready for use in the assembling of dry cells.

With this object in view, the liner consists of paper or other cellulose absorbent medium which is wound into a hollow tube of the desired size and shape. The tube thus produced is cut into the required lengths ready for insertion into a dry cell.

The invention will be more completely understood from the following description of an embodiment thereof and the appended claims. While disclosed in connection with a tamped cell, the liner forming the object of the present invention is applicable also to other types of dry cells, e. g., in which the depolarizing unit is in the form of a bobbin, compacted tablets, or washers, etc.

In the drawings, Fig. 1 is a perspective view of a paper liner wound into a tube, and Fig. 2 is a vertical cross-section of an assembled battery.

1 is a ribbon of paper or other absorbent medium that may be used as a liner or "bag" for dry cells. The paper ribbon is wound in spirals by suitable machinery into a tube 2 of the desired diameter with adjacent edges overlapping as indicated at 3. Preferably, the edges 3 are fastened together by a starch or flour paste. The tube 2 is cut into suitable lengths to serve as a separator between zinc electrode 4 and the depolarizing mix 5 surrounding carbon electrode 6. The cell is sealed in the usual manner as indicated at 7. A paper disc 8 placed in the bottom of the zinc can serves to insulate the latter from the carbon electrode and the mix.

The outside surface of the tube 3, before

or after it has been cut into lengths, or the inside surface of zinc cup 4, is coated with the usual paste. Or, if so-called bag-type cells are used, the paste is poured into the zinc container 4 after the bobbin or the like, surrounded by a length of paper tubing, has been positioned therein.

It will be seen that liners formed in accordance with the present invention may be readily manufactured in large quantities and inexpensively. Their use in dry cells will do away with the customary and relatively expensive operation of forming the paper liner for each cell separately, and the employment of molded paper cups, muslin bags, or the like.

What we claim is:

1. The process of making dry cells which consists in spirally winding a paper ribbon into a hollow tube with the edges of the spirals overlapping and fastened together by means of flour paste, coating the outside of the tube with a paste containing electrolyte, then cutting the tube into suitable lengths, and inserting a length in a zinc container electrode.

2. The process of making dry cells which comprises forming a tube of absorbent material and securing the edges thereof together, coating the outside of the tube with a paste containing electrolyte, then cutting the tube into suitable lengths, inserting a length thereof into a container of a material suitable for use as an electrode, inserting the other electrode within said tube and at least partially filling the space between said other electrode and the tube with depolarizing material.

In testimony whereof, we have signed our names to this specification this 20th day of August 1924.

JAMES J. McCANN.
CHARLES G. BIRDSALL.
